CLAIM

The ornamental design for a display screen with animated graphical user interface for bacteria measuring instrument as shown and described.

DESCRIPTION

FIG. 1 is a front view of a display screen with animated graphical user interface for bacteria measuring instrument showing a first image of my new design; and, FIG. 2 is a front view of a second image thereof.

The appearance of an image sequentially transitions to another between FIG. 1 and FIG. 2. The process or period in which an image transitions to another forms no part of the claimed design. The broken lines depict portions of the display screen with animated graphical user interface for bacteria measuring instrument that form no part of the claimed design.
